US00D988186S

(12) **United States Design Patent** (10) **Patent No.:** **US D988,186 S**
(45) **Date of Patent:** **** Jun. 6, 2023**

(54) **FLAG POLE HOLDER**

(71) Applicant: **Chenliang Xia**, Yongkang (CN)

(72) Inventor: **Chenliang Xia**, Yongkang (CN)

(**) Term: **15 Years**

(21) Appl. No.: **29/843,531**

(22) Filed: **Jun. 22, 2022**

(51) LOC (14) Cl. **11-05**

(52) U.S. Cl.

USPC **D11/182**

(58) **Field of Classification Search**

(57) **CLAIM**

The ornamental design for a flag pole holder, as shown and described.

DESCRIPTION

FIG. 1 is a front and left perspective view of a flag pole holder, showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof; and,

FIG. 7 is a bottom plan view thereof.

FIG. 8 is a rear and right perspective view thereof.

The broken lines and areas within them depict portions of the flag pole holder that form no part of the claimed design.

1 Claim, 8 Drawing Sheets
